MODULATION

Nils E. Lindenblad, Port Jefferson, N. Y., assignor
to Radio Corporation of America, a corpora-
tion of Delaware

Original applications April 5, 1932, Serial No.
603,310, now Patent No. 2,052,576, dated Sep-
tember 1, 1936, and November 17, 1933, Serial
No. 698,496, now Patent No. 2,061,947, dated
November 24, 1936. Divided and this applica-
tion April 2, 1936, Serial No. 72,245

13 Claims. (Cl. 179—171)

This invention, which is a division of my co-
nding applications Serial #603,310 filed in the
nited States Patent Office, April 5, 1932, patent
2,052,576 dated September 1, 1936 and Serial
698,496 filed in the United States Patent Office
ovember 17, 1933, patent #2,061,947 dated No-
ember 24, 1936, relates to the radio art and ap-
perts especially to the modulation and electro-
magnetic propagation of radio waves, particu-
rly in the range of wave lengths below two
eters and of the order of frequencies above one
ndred fifty million (150,000,000) cycles per
cond.

One object of my present invention is to pro-
de a modulation system for extremely short
ave length oscillations of electrical energy.

My present invention will be described more
lly hereinafter from which many other ob-
cts, features and advantages of my present in-
ntion will become self apparent.

In the accompanying drawing, the single figure
ows means for multiplying high frequency os-
illations and modulating the same.

In my United States application #603,310 men-
ioned above, I have shown novel means for pro-
icing oscillations multiplying the frequency of
e produced oscillations, modulating the multi-
lied oscillations, and propagating the same. In

the present application I disclose an additional
eans for modulating oscillations produced in
ny manner such as for example, oscillations as
roduced in said application. In describing this

ovel modulation system reference will be made
the single figure of the drawings. The waves
be modulated may be supplied from any source

a line AS of the character described in said
application, and when modulated in a manner
escribed more in detail hereinafter may be sup-
lied from the line AS to any load which may be

line or an antenna system. A magnetic modu-
ator MM comprising tubes 26 and 28 is used
absorb energy from line AS. The tubes have

ir grid electrodes connected as shown by by-
assing condensers 6 and 8 to maximum voltage
oints 7 and 9 on the line AS or, in other words,
t high impedance points. The absorption cir-
it is completed by connecting the filaments of

the tubes 26 and 28 together by the circuits 32.

The modulation circuit is completed by connect-
g a point on the impedance 34, which may

pply the heating current to the filaments of
ubes 26 and 28, to a reactor 24 which is con-
ected as shown to the anodes of tubes 20 the

athodes of which are grounded. This point on

4 is also connected to ground by an audio fre-

quency by-pass condenser 4 which fixes this
point on 34 and the adjacent end of 24 at ground
audio frequency potential. One purpose of 4 is
to complete the audio frequency circuit through
24 and tubes 20. The impedances of tubes 20
are shunted by a biasing resistance 33 which is
in series with a grid leak resistance 30 connected
between the grids and cathodes of tubes 26 and 28.
Direct current potential for both the modulator
tubes 20, and the magnetic modulator tubes 26
and 28, is supplied through conductor 22. The
modulator reactor or audio choke 24 is chosen
so as to have practically no direct current re-
sistance. Consequently, the grids and filaments
of the modulator tubes 26, 28 will be at the
same direct current current potential except for
the drop in direct current potential across re-
sistor 30. However, since the current drawn
through choke 24 is constant because of its in-
herent action, the voltage across resistor 33 con-
nected between the anodes and cathodes of the
modulator tubes 29, will vary according to the
modulating potentials due to the varying current
flow in 33. Consequently, the voltage upon the
grids of the modulator tubes 26, 28 will vary as
a result of which varying amounts of current
will be drawn or absorbed from circuit AS.

The arrangement shown here offers the ad-
vantage that blocking condensers, such as used
in the modulation circuit of the parent applica-
tion, are unnecessary. Moreover, this arrange-
ment shown has the added advantage that, be-
cause of resistance coupling, the circuit is ex-
tremely stable, is of fine fidelity, and greatly
simplifies operation.

The filament circuits 32 of the modulator tubes
may be tuned as in the parent application but
need not necessarily be tuned in the present ar-
rangement. When the filament circuits of the
absorber tubes are tuned the filaments and cir-
cuits are balanced or at ground radio frequency
potential. The circuit 2 may be tuned to the
frequency of the waves AS.

The anodes of tubes 26 and 28 may be left
“floating”, that is, completely disconnected, or
may be short circuited, or may be connected as
shown by a circuit 12 tuned to the frequency of
the waves in AS.

The solenoids 14 of the magnetic modulator are
energized by a variable source 16 in a circuit in-
cluding said solenoids and a variable resistance
18. The solenoids produce a magnetic field par-
allel to their axes which are at right angles with
respect to the electron paths of the tubes.

It has been found that if one attempts to mod-

ulate, with conventional schemes, the energy in the absorption circuit, for example, by-passing that circuit to ground through a variable impedance in the form of electron discharge devices, variations in the direct current through the impedance device in accordance with modulating potentials will produce only infinitesimal effects upon the energy in the absorption circuit. This is due to the fact that the capacitance of the device prevents any appreciable electron moving voltage to build up at these very high frequencies. Only by careful lining up of the electrons will it be possible to make them respond to these small voltage variations. Moreover, the low electron velocity within the ordinary tubes also mitigates against their use as modulators. However, with my improved tube absorbing circuit comprising tubes 26 and 28, modulation is readily accomplished as the characteristics of the tubes are greatly changed, with the application of the magnetic field thereto. This field is as shown perpendicular to the normal path of the electron stream from the cathode to the anode.

This field causes the electrons emanating from the filaments to follow curved paths so that the emitted electrons after leaving the filament are forced back and are retained in large numbers in suspension about the cathode and in the grid space. Thus, by causing the electrons to be suspended in orbits near the grid, due to the effect of the magnetic field, a greater number of electrons are available to be effected by modulating potentials. The grids are in this case biased so that electrons of tangential motion versus the grid are at all times available in great numbers in the extreme vicinity of the grid so that even though low, potentials of low or high frequency can spend work on the same with the result that absorption takes place. To vary the potential level upon the control grids of the magnetic modulator, thereby varying the absorption of energy by making a greater or smaller number of electrons available and thereby accomplishing modulation of the waves in the absorption circuit, modulation from 20 is applied to 33 to produce therein a potential drop characteristic of the signal variations which is impressed on the grids of the magnetic modulator.

I claim:

- 50 1. A system for absorbing high frequency energy from a high frequency circuit comprising an electron discharge device having an electron emitting cathode, and a control electrode, means for connecting said control electrode to said high frequency circuit, a connection between the cathode of said device and a different point on said high frequency circuit, an audio frequency impedance of low direct current resistance connected at one terminal to the cathode of said device, an additional impedance connecting the other terminal of said audio frequency impedance to the control electrode of said device, and means for applying potentials to said last named impedance which vary at signal frequency said control electrode potential varies at signal frequency and said control electrode-cathode circuit absorbs energy from said high frequency circuit in accordance with variations in the potentials of said control electrode.
- 70 2. A modulating system comprising a high frequency circuit having voltage maximum points, said circuit having flowing therein high frequency currents to be modulated, a pair of electron discharge devices each having an electron emitting cathode and a cold electrode, means connecting
- 75

said cold electrodes to voltage maximum points in said high frequency circuit, impedance means connected to the cathodes of said devices, an additional impedance connecting said first impedance to the cold electrodes of said devices, a means for applying a potential which varies at signal frequency in shunt to said first named impedance for varying the conductivity of said devices thereby varying the amount of energy diverted from said high frequency circuit.

3. Apparatus as recited in claim 1 wherein means is provided for subjecting the electron stream of said device to a magnetic field.

4. Apparatus as recited in claim 2 including means for applying a magnetic field to said electron discharge devices to thereby improve the operation thereof.

5. In a system for absorbing high frequency energy from a high frequency circuit in accordance with signals, an electron discharge device having an electron emitting cathode, and a control electrode, means for connecting said control electrode and cathode to spaced points on said high frequency circuit, a reactance of low direct current impedance connected to said electron emitting cathode, an impedance connected to said reactance, an impedance connecting said reactance to the control electrode in said device and means for producing current flow in said first named impedance which varies in accordance with signal potentials.

6. In a system for absorbing high frequency energy from a high frequency circuit in which said energy is flowing at signal frequency, a pair of electron discharge devices, each having an electron emitting cathode and a control electrode, a tuned circuit connecting the control electrodes of said discharge devices to points of high impedance on said high frequency circuit, a connection between the cathodes of said devices, an impedance and a reactor of low direct current impedance connecting the control electrodes of said electron discharge devices to the cathodes of said electron discharge devices and means for applying potentials which vary at signal frequency to said impedance.

7. In a system for absorbing high frequency energy from a high frequency circuit in which said energy flows at signal frequency, a pair of electron discharge devices, each having an electron emitting cathode and a control electrode, a reactive circuit connecting said control electrodes to points of high impedance on said high frequency circuit, means connecting said cathodes together, an additional thermionic discharge device having its anode connected to the cathode of said first pair of discharge devices, a reactor of low direct current impedance in said connection an impedance connected between the control electrodes and cathodes of said first named devices, an impedance connected between the anode and cathode of said additional device and means for varying the anode to cathode impedance of said additional device at signal frequency.

8. A system as recited in claim 6 wherein said discharge devices each include an additional electrode and in which said additional electrodes are connected together.

9. A system as recited in claim 7 wherein said first named discharge devices each have an additional electrode and wherein said additional electrodes are connected by a reactive circuit.

10. In a system for absorbing radio frequency energy from a radio frequency circuit in accordance with signals to thereby modulate said radio

frequency energy at signal frequency, an electron discharge device having an electron emitting cathode, and an additional electrode, means for connecting said additional electrode to said radio frequency circuit, separate means for connecting said cathode to a second point on said radio frequency circuit, a reactance of low direct current impedance connected to said electron emitting cathode, a connection of low impedance to audio frequency energy connecting said reactance to a point of substantially fixed potential, an impedance connecting said reactance to said additional electrode in said device and means for producing potentials on a terminal of said impedance which vary in accordance with signal potentials.

11. A system as recited in claim 10 wherein magnetic means is provided for producing a magnetic field perpendicular to the normal path 0 of the electron stream from the cathode to said additional electrode to thereby improve the operation of the modulator.

12. In a modulation system, a high frequency circuit having flowing therein high frequency currents to be modulated, a pair of electron discharge devices each having an electron emitting cathode and an additional electrode, means connecting said additional electrodes to spaced points on said high frequency circuit, impedance means

connected to the cathodes of said devices, an additional impedance connecting said first impedance means to the additional electrodes of said devices, and means for applying a potential which varies at signal frequency to said first named impedance means for varying the conductivity of said devices, thereby varying the amount of energy diverted from said high frequency circuit. 5

13. In a system for absorbing high frequency energy from a circuit in which high frequency energy flows to thereby modulate said energy in accordance with signals, an electron discharge device having an electron emitting cathode and a control electrode, a tuned circuit connecting said control electrode to a point of high impedance on 10 said high frequency circuit, separate means connecting said cathode to a second point on said high frequency circuit, a reactor of low direct current impedance and an impedance in series connecting the electron emitting cathode of said device to a point of substantially fixed potential, 15 a condenser in shunt to said reactor and impedance, an additional impedance connecting a point intermediate said reactor and said first named impedance to the control electrode of said discharge device and means for varying the current flow in said first named impedance at signal frequency. 20 25
